UNITED STATES PATENT OFFICE

102,135

DESIGN FOR AN ASTROLOGICAL CHART

Warren P. Goshorn, Kansas City, Mo.

Application September 28, 1936, Serial No. 65,039

Term of patent 7 years

To all who it may concern:

Be it known that I, Warren P. Goshorn, a citizen of the United States, residing at Kansas City, in the county of Jackson and State of Missouri, have invented a new, original, and ornamental Design for an Astrological Chart, of which the following is a specification, reference being had to the accompanying drawing, forming a part thereof.

Fig. 1 is a plan view of an astrological chart, showing my new design.

Fig. 2 is an edge view of the same.

I claim:

The ornamental design for an astrological chart, as shown.

WARREN P. GOSHORN.
